UNITED STATES PATENT OFFICE

160,558

EXPANSIBLE WATCH BAND OR SIMILAR
ARTICLE

Kurt Speck, Palisades Park, N. J., assignor to
Jacques Kreisler Manufacturing Corporation,
North Bergen, N. J., a corporation of New Jersey

Application December 17, 1949, Serial No. 6,684

Term of patent 7 years

(Cl. D45—4)

To all whom it may concern:

Be it known that I, Kurt Speck, a citizen of the United States, residing at Palisades Park, in the county of Bergen and State of New Jersey, have invented a new, original, and ornamental Design for an Expansible Watch Band or Similar Article, of which the following is a specification, reference being had to the accompanying drawing, forming part thereof.

In the drawing:

Fig. 1 is a front elevational view of an expansible watch band embodying my new design, with the conventional end links shown in broken lines and the links shown in full lines being continuous throughout the length of the band as indicated by broken lines across the center of the band;

Fig. 2 is a rear elevational view of the band as shown in Fig. 1;

Fig. 3 is an edge view thereof taken from the top of Fig. 1; and

Fig. 4 is a front elevational view similar to Fig. 1, illustrating the links in an expanded position.

The dominant feature of my design for an expansible watch band resides in the top links thereof.

I claim:

The ornamental design for an expansible watch band or similar article, substantially as shown and described.

KURT SPECK.
